UNITED STATES PATENT OFFICE.

JAMES J. DEEGAN, OF SACRAMENTO, CALIFORNIA.

LOCOMOTIVE DRAFT DEVICE.

Application filed July 15, 1925. Serial No. 43,788.

The present invention relates generally to improvements in locomotive fire boxes and has for its general object to provide means for uniformly distributing a draft of air to the fire bed and for introducing a current of preheated air into the combustion space and from the rear end of the fire box, whereby thorough combustion of the combustible gases is effected at the central and rear portions of the combustion chamber in order to produce a flame of maximum heat intensity for impingement upon the crown sheet of the boiler or front end of the combustion space.

15 The above and other objects are accomplished by instrumentalities pointed out in the following specification.

The invention is clearly defined in the claim.

20 A satisfactory embodiment of the invention is illustrated in the accompanying drawings forming part of the specification and in which—

Figure 1 is a vertical longitudinal section 25 taken through the fire box of a locomotive and showing portions of the locomotive by full and dotted lines, and further showing my invention partly in side elevation and in section.

30 Figure 2 is a transverse section on the line 2—2 of Figure 1, looking in the direction of the arrow.

In the drawings, 5 indicates the fire box of an ordinary locomotive 6. In carrying 35 out my invention with the fire box 5 I provide at the rear end thereof an air chamber 7 extending vertically upward from the grate 8 and well into the combustion space of the box 5 or, in other words, to a point 40 adjacent to the lower side of the door opening 9 of box 5. The chamber 7 extends transversely of the rear end of the box 5 and is defined by the presence of an outer wall 10 and an inner wall 11 arranged in 45 spaced relation to the outer wall and formed of any suitable refractory material, such as fire brick. One or more open-ended passages 12 are formed in the inner wall 7 and located so as to effect communication be- 50 tween the combustion space of box 5 and chamber 7. In the embodiment shown a lower passage 13 is also provided in inner wall 11 and located below the combustion space of box 5, so that the chamber is placed 55 in thermal contact with the box 5. The

upper end of chamber 7 is closed by a wall 14 and in like manner the lower end of the said chamber is closed by a wall 15. An air inlet pipe 16 extends upwardly through the lower end wall 15 and into chamber 7. The 60 passage through pipe 16 is controlled by a gate valve 17 to the cage 18 of which one end of the pipe 16 is connected, and a stem 19 connected to the gate valve 17 and also to a manually operable lever 20, preferably located in an accessible position in the cab 21, is provided for operating valve 17 to open and close.

A chamber 22 within cage 18 is connected to an air supply pipe 23 and communication 70 between the chamber 22 and inlet pipe 16 is controlled by the gate valve 17. The air supply pipe 23 is connected to a blower 24 which may, as shown, be mounted upon the tender 25, a shaft 26 being employed for 75 connecting the blower 24 to a motor of any preferred type, such as a steam turbine 27 which is connected in operative relation to the boiler head of the locomotive by a pipe 28. 29 is an air inlet pipe connected to cage 80 18 and in constant communication with chamber 22. The pipe 29 extends forwardly and underneath the grate 8 and its forward end is provided with an air distributor hood 85 30 of any preferred construction adapted for distributing jets of air outwardly and upwardly in a plurality of directions through the spaces between the bars of grate 8.

In the operation of the device as described 90 and when valve 17 is open, the air upon entering chamber 7 from pipe 16 is readily heated by the heat from the fire bed passing through opening 13. The air thus heated is rarefied and so enters the combustion space 95 through openings 12. In its rarefied state the oxygen of the air more readily combines with the burning gases in the combustion space and thereby promotes combustion so that the heat of the resulting flame is of 100 maximum intensity when it moves forwardly and impinges upon the forward end of the combustion chamber or bottom of the crown sheet. This property of the present construction to promote combustion in the 105 rear end portion of the fire box is of importance, in that there results a thorough combustion of all combustible gases so that practically no carbon is deposited within the tubes of the boiler, and the heat is applied 110

where most needed, to wit, upon the crown sheet.

It is to be noted that the result just mentioned on the part of the present construction, is to be readily distinguished from instances where the course of the draft is from the front end of the fire box and upwardly through the fire and into the front end of the combustion chamber. In the latter case combustion at the rear end of the fire box is relatively small and the partly consumed gases enter the boiler flues and operate to carbonize the same and, at the same time, the air moving upwardly through the front end of the fire box, operates to reduce the temperature of the fire box below that had with the present construction.

It is to be noted that the location of the hood 30 insures of a uniformly distributed up-draft through the fire bed to promote combustion therein. The present construction also eliminates the use of a relatively small orifice in the end of the exhaust pipe of the locomotive and located within the stack thereof, in that a relatively high velocity on the part of exhaust steam is not necessary to create a draft through the flues necessary to draw a sufficient quantity of air into the fire box to promote combustion therein. Obvious then with the present construction, back pressure in the cylinders can be reduced to a minimum.

If so desired, a tubular lead 31 may be extended from the feed water heating pipe 32 and connected to the inlet pipe 16 so that the exhaust steam in pipe 32 may be utilized

in heating the air in chamber 7 in addition to the fire bed as previously described.

Although I have shown and described one embodiment of my invention, it is to be understood that the same is susceptible of various changes; and I reserve the right to employ such as may come within the scope of the appended claim.

I claim:

In a locomotive fire box having the rear end thereof formed of outer and inner walls spaced one from the other to provide an intervening air chamber in thermal contact with the interior of the fire box, the inner of said walls having in its upper portion a transverse opening disposed so as to effect communication between the chamber and the combustion space of the fire box, means for directing a current of air upwardly through the chamber and outwardly through the opening thereof and into the combustion space and further for directing a current of air upwardly through the fire bed and including a power operated blower, an air take-off pipe connected to the blower, two conduits one of which is directed into the lower end of the chamber and the other of which is directed so as to distribute air underneath the fire box, a valve casing having separated portions to which the conduits are respectively connected and an intermediate portion connected to the air take-off pipe, and a valve in the casing for controlling the passage of air from the take-off pipe through one or both of the conduits.

JAMES J. DEEGAN.
